WILLIAM H. HALL, OF MALONE, NEW YORK.

Letters Patent No. 86,011, dated January 19, 1869.

IMPROVED RAILWAY-CAR COUPLING.

The Schedule referred to in these Letters Patent and making part of the same.

To all whom it may concern:

Be it known that I, WILLIAM H. HALL, of Malone, in the county of Franklin, and State of New York, have invented a new and improved Car-Coupling; and I do hereby declare that the following is a full, clear, and exact description thereof, which will enable others skilled in the art to make and use the same, reference being had to the accompanying drawings, forming part of this specification, in which—

Figure 1 is a top view of my improved car-coupling.

Figure 2 is a longitudinal vertical section of the same through the line $\alpha\alpha$.

Similar letters of reference indicate like parts.

The object of this invention is to provide a simple and effective self-acting car-coupling.

It consists, in general terms, of a coupling-head or bunter, so called, formed with a vertical longitudinal slot extending through the upper part of the bunter, down to the cavity of the same, and in which is pivoted a coupling-link of peculiar construction, and which is a link continuous with and forming part of a coupling-pin, through which latter the pivot-bolt of the bunter passes.

When the link is thrown back upon the bunter, the pin is brought in place within the cavity of the bunter, and is encountered by the coupling of the next car when moved up to be coupled, the link of the said car entering the mouth of the bunter, and pressing back the pin sufficiently to allow the forward end of the link to pass the pin, when the latter will slip inside the link and regain its former upright position.

The pin is actuated, to recover its upright position, as described, by the weight of the link-part, which acts as the weighted arm of a right-angled lever.

The invention will be better understood by reference to the drawings, in which—

A is the bunter;

B, its vertical slot; and

C D, the combined pin and link, arranged in the slot

B, and pivoted on the bolt E, extending from side to side of the bunter and through the slot.

G is the cavity of the bunter, and

H is any common link, inserted therein, to illustrate the operation of the pin.

The pin D projects down from the slot into the cavity of the bunter, as shown, when its link-part C is thrown backward upon the bunter, for the link, in its general longitudinal dimensions, forms nearly or quite a right angle with the pin-part D.

In practice, each end of each car is provided with a bunter, and its link and pin, and one of the links is thrown forward to serve as a coupling-link, in which case the link is brought down to the position shown by the common link H, while the pin-part projects upward out of the way.

The slot B extends back far enough to permit the upward passage of the pin when the link C is thrown forward.

This coupling may be used with a common link, H, or either of the links C of one of the couplings may be used as a coupling-link.

Having thus described my invention,

I claim as new, and desire to secure by Letters Patent—

1. The combination of the slotted bunter A with the combined link and pin C D, pivoted in the slot B of the bunter, and arranged to operate substantially as described.

2. A coupling-device, consisting of a link, C, and pin D, arranged at right angles to each other, and provided with a hole for a pivot-bolt, or other known means, for pivoting the said device in a coupling-head or bunter, so as to operate substantially as described.

WILLIAM H. HALL.
